UNITED STATES PATENT OFFICE

161,988

KNITTED MITTEN OR THE LIKE

Robert K. Adams, New York, N. Y.

Application February 10, 1950, Serial No. 7,890

Term of patent 7 years

(Cl. D3—11)

To all whom it may concern:

Be it known that I, Robert K. Adams, a citizen of the United States of America, residing at New York city, in the county of New York and State of New York, have invented a new, original, and ornamental Design for a Knitted Mitten or the like, of which the following is a specification, reference being had to the accompanying drawing, forming part thereof.

In the drawing:

Fig. 1 is a front elevational view of a knitted mitten or the like showing my new design;

Fig. 2 is a rear elevational view thereof; and

Fig. 3 is a side elevational view thereof.

I claim:

The ornamental design for a knitted mitten or the like, substantially as shown.

ROBERT K. ADAMS.
